UNITED STATES PATENT OFFICE

2,237,401

DISINTEGRATOR

Charles T. Asbury, Elkins Park, Pa.

Application August 6, 1938; Serial No. 223,481

13 Claims. (Cl. 83—7)

My invention relates to colloid mills and like devices for homogenizing, emulsifying, dispersing or otherwise disintegrating or distributing liquids, emulsions, solids capable of liquefaction and solids in suspension within liquids for the purpose of reducing the sizes of the particles of which they are made up.

One purpose of the invention is to make high speeds of disc disintegrators available to a maximum by feeding the material to be disintegrated to them at their circumferences.

A further purpose is to secure high speed impact while avoiding excessive temperatures and avoiding wear.

A further purpose is to deliver rapidly repeated high speed impacts upon the particles of a treated stream.

A further purpose is to use the end surface of a high speed impactor to guide and assist in feeding a stream of particles to the outer part of the impactor, to feed the stream from the end into position to be struck by impact teeth or blades carried by the impactor, thereby subjecting particles to blows and giving them high speed and to clear the spaces between the teeth or blades by sloping the blade faces away from the direction of movement.

A further purpose is to drive a stream circumferentially by the blades or teeth of an impactor and to clear the particles of the stream therefrom diagonally against fixed roughened surfaces so as to deliver additional impacts by engagement of the stream with the fixed surfaces.

A further purpose is to use one or more high speed impellers as impactors against a stream of particles to be treated, feeding a stream of particles of low circumferential velocity into an impeller having high circumferential velocity and thence, through fixed guiding surfaces into a second impeller of high circumferential velocity.

A further purpose is to taper the engaging surfaces of an impactor or impacting rotor away from the direction of rotation so as to give a diagonal direction of discharge, in order that the radial component of the discharge will carry the stream acted upon out against the surrounding casing and insure as well as speed up clearing of the stream treated from these limiting surfaces.

A further purpose is to interrupt film flow of a material treated over a fixed guiding surface in spaced relation adjacent a rotor to prevent bypassing and insure full treatment of materials passing therethrough.

A further purpose is radially to interlap a rotor edge and a stator guiding surface about it.

A further purpose is to guide a liquid to be disintegrated axially, radially and then again axially from one disintegrator rotor for the purpose of delivering it into the outer part of the end of another disintegrator rotor.

A further purpose is to subject a stream of particles to be treated to a succession of high speed impacts, using the fixed surfaces adjacent to guide the stream between impact points and permissibly using the guiding surfaces also as impact surfaces.

A further purpose is to treat a stream of particles by high speed blows from an impactor at the circumference and turn the stream across another and permissibly still other impactors, intermediately delivering blows to the particles within the guiding section.

A further purpose is to provide a plurality of disintegrators rotating at high speed and permissibly driven as a unit, in each of which disintegrators the material acted upon enters axially near the circumference, and, in all beyond the first of which, the previous disintegrator and its surrounding fixed cooperating surfaces guide and speed the stream acted upon so as to enter the successive disintegrators laterally.

A further purpose is to groove guiding fixed surfaces cooperating with one or more rotary disintegrators and interlap the disintegrators with these grooved surfaces.

A further purpose is to use a plurality of rotors revolving at high speed and having impact with a nearly stationary colloid at or near their outer circumferences, the impact element of one rotor preferably being staggered with respect to the adjacent rotor.

A further purpose is to engage a stream of particles with a disintegrator first near the circumference of the disintegrator, feeding into it axially from the end and discharging circumferentially against adjacent fixed structure, interlapping the outer part of the disintegrator with a cooperating groove and discharging the stream axially into a larger disintegrator having its impact surfaces and openings preferably staggered with respect to the first, immediately to receive the discharge.

Further purposes will appear in the specification and in the claims.

My invention is directed to the methods involved as well as to mechanism by which these methods may be carried out.

In the disintegration of colloid, quasi colloid and other materials it is very desirable that the disintegration be as complete as possible and that

the extent of disintegration be as great as possible within a minimal distance of treatment.

In the method and structure which I have presented I have aimed to condense the disintegration of materials within a minimal structure and minimal space in order to make the structure as compact as possible and to reduce intermediate material movement between disintegrating treatments of the material.

I have preferred to illustrate the invention by one general form only with slight modification, selecting a form which is practical and efficient and highly advantageous but which has been chosen primarily because of its excellence in illustrating the principles of the invention.

Figure 1 is a vertical elevation partly in section showing my invention as applied to a mill having a single disintegrating rotor only. The upper part is sectioned to show this feature.

Figure 2 is a section on line 2—2 of Figure 1.

Figures 2a and 2b are fragmentary top plan views of modifications of the disc shown in Figure 2.

Figure 3 is a fragmentary section corresponding generally to Figure 1 but showing three disintegrating rotors acting together.

Figure 4 is a top plan view of the group of rotors seen in Figure 3, corresponding to a section staggered between the composite rotor and the stationary surfaces with which the rotors cooperate.

Figures 5 and 6 are enlarged fragmentary sections showing the composite rotor with adjacent stator of Figure 3 and an alternative construction respectively.

Figure 5a is a fragmentary section corresponding generally with Figure 5 but showing a modification.

Figure 5b is a fragmentary vertical radial section through a disc modified with respect to that of Figure 5.

In the drawings similar numerals indicate like parts.

In industrial and scientific fields there is need of certain non-homogeneous discontinuous mixtures variously called emulsions or dispersions. The emulsification or dispersion can be accomplished in a number of ways, the most important of which involve mechanical mixing and agitation. The more violent this treatment can be made, in general, the finer will be the subdivision of the individual globules, droplets or particles. Such treatment is variously called homogenization or disintegration. Because the treatment is mechanical, it will be referred to herein more generally as disintegration.

From two general types of homogenizers or disintegrators in common use I wish particularly to clear. The one passes a stream to be treated through a very small space between a rotor and a casing, the space being so small that the operation is almost akin to grinding. Excessive heat is developed and the size of the particles produced varies greatly, partly because of the variation in the temperature. The capacity of this type is low, pre-grinding is often necessary and the wear upon operating parts is excessive.

The other type known as a viscolizer is necessarily of heavy construction, presents difficulty in cleaning, requires excessive power, is applicable only to liquids and also is subject to excessive wear.

It is my intention in referring to the colloid mill as a disintegrator, etc. to cover the use of such a mill and such methods as are disclosed herein, broadly or specifically, for use upon

liquids, solids in suspension or solids wherever it is found to be useful.

Because mechanical disintegration itself supplies the heat necessary for liquefaction of fats and oils in certain solids containing them, for example, such as found in the peanut and in chocolate nibs, my invention is suitable for treatment of solids of this character as well as of solids very high in water, solids in suspension in liquids and true liquids. In the case of solids such as coffee, there will be complete pulverization.

The present invention is based upon the principle of applying high speed impact to initial breaking up of the particles into smaller particles and successively applying further high speed impacts to successively reduce the size of the particles. As the materials treated will largely be colloids the designation colloid will be adopted generally, for convenience, as covering all materials to which the invention may be applied.

The single rotor impact wheel or disc by which I have preferred to illustrate the first part of the invention is seen in Figures 1 and 2. Here the base 10 supports a rotor shaft 11 driven preferably by a motor within or forming part of the base. About the rotor shaft is fixedly supported a casing 12 of which the cap 13 forms a part.

Within the cap the colloid to be homogenized or disintegrated may be introduced in any suitable way. In the illustration it flows in through the pipe 15 but does not fill the space above the rotor. If excessive colloid be forced in or flow in, particularly if the space 14 becomes filled with colloid the friction immediately becomes excessive, interfering with and ordinarily completely stopping operation.

The rate of colloid feed which is desirable is easily determined by the performance of the mill. Central entry is desirable to preserve balance. The colloid then spreads by centrifugal force along the end face of the rotor 16, but without much circumferential speed, from the center to the outer part of the face or end of the rotor.

The cap is fastened to the lower part of the casing by bolts 17 passing through a gasket 18. A diagonal division plate 19 may be secured by the same means and, however secured, provides a bottom and guides drainage of the homogenized product from the point at which it is treated to an outlet discharge nozzle 20 shown at the left in Figures 1, 2 and 3.

The shaft 11 not only carries the impact disc 16 but also supports an inverted cup 21 which reaches down over the upper end of a cylindrical shield 22 so as to prevent the treated product from engaging the shaft 11. This avoids the necessity for any attempt at close bearings between these parts and places the effective bearings of the rotor and of its shaft below the casing.

The rotor disintegrator is held to the shaft by any suitable means, here shown at 23. The greater part of the upper surface 24 of the disc with which the colloid engages and upon which in one character of operation the colloid is deposited, is preferably plane as it is not the wish to use it to bring the colloid up to any considerable circumferential speed but only to cause flow of the colloid out along the disc surface to the circumference of the disc.

The radial distribution of the colloid can best be accomplished by just enough circumferential speed of the colloid to feed by centrifugal force.

The rotor operates by reason of teeth or projections 25 at its circumference. These teeth

are rendered effective by kerfs or slots 26 which preferably are not radial but instead slope at an angle lagging with respect to the radius and slope sufficiently to cause practical clearing of the colloid from the teeth. The angle is shown in Figure 2 as that between radius 27 and a line 28 through the edge of the tooth. The slots result in the teeth having leading faces 29 and trailing faces 30 with the slots between.

It is recognized that the extent of angle of the slots does not have any sharp and fixed value but may be varied considerably to get good results and that it should be somewhat greater for a solid or relatively dense liquid treated than for less dense or more easily flowing "liquids" treated, including as "liquids" fluids in which solids are suspended in liquids. Fair results have been secured upon some highly fluid colloids with radial slots. The range of colloids which can be handled (with respect to their freedom to flow and their effective discharge) increases with the angle in the low angle range. Excellent results have been secured with a wide variety of solids, liquids, and solids in suspension in liquids with angles ranging from zero (radial) to fifteen degrees (15°).

The upper face of the disc as the disc lies in Figure 1 is circumferentially grooved near the perimeter to provide a shallow channel 31 within the area which is slotted to form the teeth, leaving an upwardly directed annular flange 32 as the outer limit of the channel and an annular shoulder 33 at the inner channel limit.

The disc 16 cooperates with a fixed baffle or guide 34 mounted within or formed from the cap of the casing in any suitable way and preferably with fixed impact surfaces roughened or otherwise formed to abruptly divert the direction of flow of the guided discharge from the impact disc.

The baffle provides a downwardly extending ring 35, preferably extending down into the annular groove 31. A downwardly directed annular groove 36, lies between the rib and the outer casing wall.

The lower outer edge 38 and the shoulder 39 of this rib 35 is abrupt enough (preferably less than 90°) and steep enough, with cooperating groove depth, of course, to break up the travel of a film of colloid along the lower surface of the baffle which would flow by reason of centrifugal force and otherwise would follow the baffle surface because of capillary attraction. Any particles discharging from the sharp outer edge are caught by the flanged portions of the teeth at 32.

The rib and groove of the annular baffle are so placed that the rib lies over the channel 31 and the groove lies over the flange 32. The operation is quite materially more effective when the rib extends down into the channel and when the flange 32 lies within the space of the groove 36 than if the parts are located so that this relation does not exist.

The discharge from the disintegrating rotor is concentrated largely upon the adjacent surface of the casing and the outer portion of the groove. In order that they may not only act as impact surfaces but properly clear the colloid from their own surfaces and feed the colloid either to its point of discharge or—as in other figures to another rotor—I fill in the space between the baffle and the casing by material welded into position at 40 to give a curved and ultimately outwardly and downwardly sloping guiding surface 41, Figure 5a in the illustration, finding this manner of forming this surface slightly more advantageous

than would be a continuation of the baffle. The baffle must be connected to the casing in some way here and the welded filling presents a better wearing guide than does the material of the baffle.

The impact effect upon the stream of colloid from contact with this surface 41 is improved by roughening the surface which may be done for example by sand blasting. I recognize that a great variety of surfaces is available for roughening so that the energy of the stream will be taken up largely in impact leaving just enough velocity to clear the surfaces so as to avoid cushioning of the colloid and provide feed to the point of discharge, or as in other figures, to the spaces between the teeth of another rotor disintegrator; but my invention relates particularly rather to the matter of roughening than to the character of the roughening of the surface, or the manner in which the roughening of the surface is secured. There is sufficient clearance between the periphery of the disc and the casing to provide free discharge of the treated stream.

The inlet pipe 42, may be kept filled with colloid in order to avoid admission of air from above. The valve 43 in this pipe controls the flow of colloid to avoid filling the space above the disc.

As thus illustrated, the colloid to be treated flows outwardly but with low circumferential speed along the preferably plain surface of the disc from the inlet until it reaches the inner limits of the teeth or projections where it flows in part outwardly and downwardly into the groove and into the spaces between the teeth and in part against the baffle. I have had great success with impeller speeds of the order of five thousand peripheral feet per minute and at any such speed the colloid as it flows into the spaces between the teeth receives terrific impacts or blows from the forwardly directed surfaces 29 of the teeth which are highly effective in homogenizing the colloid.

The blows are the more effective because the slots are narrow and the slots are not fully filled. The volume of colloid in each slot is small enough to offer little cushioning and be almost wholly homogenized. With a disc diameter of six inches, thickness of three-sixteenths of an inch, slot width of one-eighth of an inch, slot angle of 15° and tooth length of seven-sixteenths of an inch the speed above gives excellent results homogenizing as diverse materials as cold cream, bananas, mineral oil emulsions and ground peanuts.

At the same time the advancing tooth surfaces deliver blows they cause the colloid to be carried with the disc and to partake of the speed of the disc, with the result that as the stream is discharged from the disc against the adjacent stationary structure, whether it be smooth or deliberately roughened, the particles in their now partially divided form again receive terrific blows at differential speeds comparable with those delivered by the teeth.

Whatever is later to be done with the colloid stream to which the teeth deliver blows, this stream is cleared quickly from the slots, kerfs or spaces between the teeth, maintaining the capacity of the impact disc and avoiding having colloid which too sluggishly clears act as a cushion to soften the blows delivered.

If the slots were radial the material treated, if in the least sluggish, would but poorly discharge from the slots themselves, being then

dependent unduly upon the centrifugal force of the colloid which would not yet have gathered speed from centrifugal force because it had so recently entered into the slots. The angular position of the slots with respect to the radius gives a wedge-like effect which tends to eject the colloid from the slots more forcefully and at higher speeds and gives an additional radial velocity component in addition to the tangential velocity component to the streams when they emerge from the slots.

The direction of discharge from the rotor due to the wedge action is therefore diagonal both to the radius and to a tangent to the disc at this point and this diagonal direction of stream discharge increases the impact of the discharged material against the fixed surface and gives a desirable clearance to this discharge from the fixed surface whether this fixed surface be circumferentially smooth (Figure 2) or circumferentially roughened as in Figure 5a.

Though the single rotor disc form seen in Figure 1 does excellent work in disintegrating, it does not carry the disintegration as far as it can be carried by a combination of disintegrating discs.

In the multiple disintegrator forms of Figures 3-6 the discharge from the first rotor is guided by a fixed annular baffle quite similar to the baffle in Figures 1 and 2 but is guided into the path of a second rotor by which the particles are further disintegrated and are discharged into a second baffle which directs the flow into the path of a third disintegrator; it being the intention to pass the flow from the first disintegrator through as many disintegrators as may be desired, with intermediate guidance, and with or without such special provision of roughening of the baffle surfaces for the purpose of intermediate disintegration. The discharge from the final rotor is guided by a baffle with or without roughened surfaces and passes into the space from which final discharge takes place.

In the preferred form of the multiple rotor disintegrator, as shown in Figures 3, 4 and 5, the smallest rotor is shown as substantially identical with the single rotor in Figure 1, using the same type of teeth, spacing of the slots, face channel and limiting flange. The additional rotors, of which two only are shown, 16¹ and 16², are successively larger than rotor 16 and rotor 16¹, respectively, and are quite similar to it in that they have corresponding teeth 25¹, 25² and corresponding kerfs 26¹, 26². Likewise, these successively larger rotors are provided with face channels 31¹, 31² and flanges 32¹, 32².

If it be desired the teeth of the successive rotors may be staggered, so that the teeth of the rotor 16², for example, shall correspond generally in angular position with the slots of rotor 16¹, as appears in the middle and outer rotor discs in Figure 4. This is fully practicable with larger diameter of discs. In such case there will be, of course, the same number of teeth on each rotor and the teeth—or the slots, or both, correspondingly will occupy a larger circumferential space in the larger than in the smaller rotors. This in no way limits the capacity of the successive rotors because the colloid flow is controlled by the capacity of the smallest rotor and each successive rotor will handle the stream which is fed to it from a preceding rotor. It will be noted that the number of teeth on rotor disc 16 is not the same as in disc 16¹.

Along the substantial duplication on a larger 75

diameter of the teeth, slots, etc., in the successive rotors applicant prefers also substantially to duplicate the fixed baffle by which the colloid is directed from the slots of the single rotor to discharge. These are nearly duplicated in the baffle guiding the flow of the colloid discharged from one rotor to the slots of the teeth of the next, and so on.

Of course it must be remembered that the baffle 10 performs disintegrating functions in Figures 1 and 2 whether there be a roughened surface or not, the roughened surface merely improving the effectiveness of this action.

Since the next succeeding rotor will do for a 15 colloidal stream discharged by one rotor, the disintegrating intended to be performed in Figures 1 and 2 in its most effective form, i. e., using the roughened fixed surface (Figure 5a, for example) and will do it better than would this 20 roughened fixed surface, the roughening of this surface may be omitted, if desired, in the guides between rotors, at least, in multiple rotor structures such as are shown in Figures 3-6 and may be omitted from the final guide if its function 25 be then not needed.

Comparing with Figures 1 and 2, it will be noted that in both of Figures 5 and 6 the smallest rotor 30 discharges into a baffle characterized by a groove 36 and downwardly directed annular rib 35. The annular downwardly and outwardly sloping surface 45 is used to direct the discharge, after impact into the channel 31¹ of the next rotor 16¹ and therefore upon the faces of and between its teeth 25 and between the teeth 25¹ of the next 35 rotor 16¹. It still has impact functions and in addition to its ultimately guiding the flow into the path of the teeth of the next disc it must intermediately divert the flow from the impact surface rapidly enough to prevent cushioning.

40 The diameter of the second rotor—and similarly of the third with respect to the second—is selected so that the teeth 25¹ and the face channel 31¹ shall be in position to receive the discharge stream directed by the surface 45. Moreover, the fact that all of the rotor discs are 45 carried by the same shaft permits an initial setting of one disc with respect to another—such as the staggered relation of 25¹ to 25² to place the slot of one opposite the solid part of the tooth of another—to be maintained. The stream discharged from rotor 16¹ is guided through the medium of annular groove 36¹ and downwardly directed annular rib 35¹, which latter fits into the channel 31¹. At the outer end of these guiding walls the downwardly and outwardly sloping annular surface 45¹ directs the flow into the channel and teeth of still another rotor 16², having diameter suited to receive the discharge from the slots of rotor 16¹.

60 Preferably the same relation is maintained between channel 31¹ and flange 32¹ on the one hand and the annular downwardly directed rib 35² and groove 36² as is maintained between the corresponding parts shown in connection with the second rotor.

65 From the rotor of largest diameter, here 16², the outwardly flowing stream of colloid discharges against a guiding and limiting wall 37 which diverts the stream downwardly into the space 46 above the partition 19. Whether the discharge 70 engage a smooth wall or a roughened wall—such, for example, as that shown in Figure 5—is a matter to be determined by the purpose to be served. In either event the high velocity of the discharge stream results in further disintegration

of the globules of the colloid, the greater disintegrator effect of the roughened surface being balanced against the tendency to throttle the discharge. Where other intermediate means have been provided for additional disintegration, such as the succession of disintegrating rotors in the present case, the use of a roughened surface at this point as a disintegrator may not be justified by the need.

In Figure 6 the effect of having the outer edge of the disc higher than adjacent part of the disc so as to enter the groove 36 is secured by turning up the edge of the disc at 47 instead of providing an annular channel as in the preceding figures. The operation is quite similar to that in Figure 5. The baffle cooperates with the flange 32^a as before and the flanged tops of the teeth receive colloid and disintegrate it much as do flanges 32, 32¹, etc.

In Figure 2a the outer cylindrical surfaces of the teeth have been relieved at 48 in order to reduce the resistance to rotation of the wheel. The cylindrical surface relieved is not operative for impact purposes as the forwardly directed face 29 of the tooth performs this function.

In Figure 2b the outer, otherwise cylindrical surfaces of the teeth slope circumferentially in this case along curved lines but in the opposite direction from the slope appearing in Figure 2a and for a very different purpose. As previously noted, the angular relation of the slots' length with respect to the radii is intended to perform the double function of assisting in clearing the colloid out of the slots and in giving an outward component of flow as distinguished from more nearly tangential flow which comes from these slots. The slope of the outer surfaces of the teeth in Figure 2b is intended for use to assist in the second function above, namely, in diverting the outward flow from the slots away from the tangent and toward the immediately adjacent baffle. Except as it may be needed for this purpose, it will normally not be desirable because of the considerable increase which it causes in the friction due to rotation of the disc or discs.

In Figure 5b teeth 49 are shown intended to be spaced by slots 26^a similar to the slots shown best in Figures 2 and 4 and to be channeled at 34 comparably with the channeling shown in the other figures. These channels result in leaving the flanges 32.

The teeth 49 in Figure 5b are comparable with the teeth in the other figures including the use of a channel 31 and flanges 32 used for the same purposes as in the other figures. However, the slots 26^a are not cut all the way through or, at least, are not cut all the way through to the full radial depth of the teeth, leaving portions 50 at the inner lower parts of the teeth which are uncut. These uncut portions at the back of the teeth may extend clear to the outer circumference of the teeth as at 51 in Figure 5b though this extent of uncut metal is not necessary to secure a part of the benefit of this invention. The form of slot bottom is a convenient form to cut because it corresponds to that of an ordinary milling cutter.

The use of slots 26^a between teeth as in Figure 5b, whether the slots be cut clear through the disc or leave uncut portions 50 extending to the outside at 51 of the disc as in Figure 5b is intended to serve a purpose in increase of suction to draw the outwardly flowing colloid down into the grooves by cutting off inlet of air from below and at the same time not to interfere with the actual flow of colloid into the teeth spaces.

It is evident that even with the slots clear through as in Figures 1-6 the colloid does not flow down to the bottom of the groove at the start, i. e., immediately adjacent the inner ends 5 of the slots. Instead, due to centrifugal force the colloid moves outwardly as it enters the slot describing a shallow paraboloid curve. Filling in with metal a part 52 which would not in any event be filled with colloid makes no difference 10 in the colloid carrying capacity of the slots, provided the metal be cut low enough to avoid friction of the colloid against the uncut wall 53.

The reason above justifies leaving a certain amount of uncut metal in the lower inner part of 15 the slots, as doing no harm, but does not justify leaving the uncut metal in the lower part of the outer part of the slots. If uncut metal be left there, it must be justified by the additional suction 20 upon the colloid flow into the slots, thus made available by cutting off inlet of the air from the bottom. Since the bottom is open to air inlet through the discharge 20, air would be filled in 25 to break the suction in the construction of Figure 1 and in the case of the lowermost disc in Figures 5 and 6 unless the air inlet be cut off by some such means as shown in Figure 5b. Such action of the inlet is avoided in the case of the uppermost and middle discs in Figures 5 and 6 by the positions of the discs below them. Where 30 air inlet is cut off by closure of the lower part of the slots between the teeth the discharging stream of colloid will protect against air inlet between the rotating disc and the baffle. However the spacing between the disc perimeter and the 35 baffle is great enough so that there is no grinding action and ample room for film flow.

The space 54 above the baffles is available for 40 heating or cooling purposes as desired. When objectionable heat is developed by the operation of the rotors cooling liquid may be applied. However, when the colloid is sticky in its character or is unduly viscous heating of the baffles 45 may become quite desirable. For the purpose of introducing either heating or cooling fluid I have shown inlet pipe 55 and outlet pipe 56.

It will be evident that the series of discs act as 45 a unit, giving a larger speed of flow for each disc in succession and a higher rate of impact in each. The sparse quantity of colloid flowing into the 50 first disc assures that there shall be no clogging of colloid in the slots of any of the other discs.

The extremely shallow depth of entry of the 55 colloid within the slots of the discs—particularly of the initial disc—makes it wholly unnecessary that the disc shall have much thickness. Ordinarily its thickness would be determined rather by mechanical requirements to avoid warping of the surface and to give stiffness than by the need of slot depth sufficient to handle the colloid.

The initial disc performs a function not required of the other discs of securing uniformity and proper rate of distribution of the colloid. In fact, this function—even if it had no other—60 would justify the use of the initial disc.

Because of the rapid radial distribution of the 65 colloid over the surface of the initial disc, there is a much greater tendency for the colloid to discharge from the upper surface of the disc without this portion of the colloid entering the slots than is true of the other discs. One of the purposes 70 of the upwardly directed flange on the outer face of the disc and of having it interlap within a groove in the guide and of the downwardly directed fixed baffle rib by which this groove is 75 emphasized is to direct the colloid down into the

channel by the radially inner face of this rib and prevent the colloid from by-passing, by requiring that as the colloid passes outwardly under the rib it shall enter the outer end at least of the slots where these slots pass through the outer flange. This is of benefit in all of the discs but has special advantage in the initial disc.

The best results are secured when the baffle rib comes down below the upper level of the disc flange, because then there is more assurance of all of the colloidal flow being dropped to at least the level of the top of the flange as the colloid leaves the disc.

As will be seen, with this preferred form the guiding function performed by the rib is independent of the question of whether there be an annular "channel" about the disc or not, since for this purpose the channel affords a convenient means of providing a flange which shall be higher than the immediately adjacent section of the disc. Another way of providing the "flange" complying with the requirements above and shown in Figure 6 secures the comparative heights without necessity for a cut channel by projecting the edge upwardly as distinguished from cutting away the adjacent upper disc.

Even if the downwardly extending baffle rib does not extend below the level of the flange a part of the benefit of my invention will be secured by its function of deflecting the colloidal stream. Where this function is performed to the full substantially all of the colloid which is distributed by the (first) rotor will pass out through the slots of the rotor, much of it passing down into what may be considered as the "bodies" of the slots and the balance passing through at least between the flange portions of the teeth.

It will be clear, therefore, that the colloid will not enter the slots of the initial disc as quickly nor as deeply as it will enter the slots of subsequent discs where its flow as it approaches the slots is nearly axial instead of along the face of the disc. It will also be clear that the path of the colloid entering the slots between the teeth of the initial disc will be parabolic, the parabola being flattened by the considerably higher speed given by centrifugal force as distinguished from that given by gravity.

Between the entry of the colloid within the slots along its parabolic track and the discharge of the colloid through the flange ends of the slots, the initial disc performs a very considerable impact function in addition to the necessary distributing function.

There are various advantages in having the additional impact discs successively of larger diameter than the next preceding impact disc. The guiding function to feed a larger disc can be performed with less reversal of direction of colloid flow than would be required if the successive impact discs were the same size or smaller. The larger diameter of each successive disc gives a higher speed of disc and therefore a greater impact blow and if we give up the idea of staggering the teeth of the later discs back of slots in the earlier discs, the larger diameter permits a larger number of slots for the same circumferential length of tooth, reducing the thickness of the film passing through each slot and therefore additionally avoiding such cushioning effect as would take place with a thicker film.

It will be evident that the danger of discharged colloid being passed through without properly entering the slots of the next disc is greatly reduced in succeeding discs by the fact that the

colloid is guided to discharge axially into the face of successive discs.

The sharp lower outer corner and undercut shoulder of the baffle result in colloid leaving the rib at this point instead of following the surface of the adjacent groove. The colloid which has left the film is thrown upon the teeth and grooves, in particular upon the tooth flanges and between the teeth at the flanges.

10 The subdivision of the colloid into successively finer particles tends to produce a mist of the colloid which tendency becomes more pronounced, the finer the subdivision. With the larger volume of mist formed, the colloid will tend to fill a larger proportion of the slot in each subsequent disc. However, when the mist is discharged upon a surface, it will tend to condense as a film but with more capacity for conversion into mist with each further subdivision of the particles.

15 The method of securing outer tooth flanges by cutting a channel and leaving the uncut metal as a flange (Figure 5) has advantage over turning up an edge (Figure 6) because the distribution of the metal about the circumference is then likely to be more uniform than that secured in the construction in Figure 6. For the initial disc there is a slight advantage also, over the Figure 6 form, in that the radially inner shoulder provided by the channel assists in breaking up the film flow of the colloid being distributed along the surface of this initial disc. This function has less utility in the other discs than in the initial disc because there is with them a much smaller proportion of colloid tending to follow the surface of the discs.

20 The determination to illustrate the invention by discs rotating in horizontal planes and carried by vertical shafts has been reached not because the invention can not be used with horizontal axis and vertical lines of rotating—for they can be so used—but because of the fact that it is easier to balance the feed of the colloid and thus to secure a high uniform distribution of the colloid flow with an upwardly facing horizontally rotating disc than with a disc rotating in a vertical plane. In determining this preference for the vertical shaft applicant has considered that the shaft difficulty of the vertical shaft construction, namely the need for thrust bearings is a purely mechanical feature not affecting the operations performed, whereas the improvement in distribution secured does seriously improve the operation of applicant's method and enables him to get maximum efficiency and ideal conditions of operation. Under the rule that the inventor, showing the best form of his invention, is entitled to cover appropriation of the invention, even in less advantageous form, applicant plans to cover in all claims not inconsistent themselves therewith, the horizontal shaft form as well as the vertical shaft form.

25 It will be evident that the spacing between the disc perimeter and the baffle is great enough so there is no grinding action at this point and so the fluid friction is low and the friction of the mechanism is largely confined to the friction of the disc against the colloid flowing and the friction of the bearings.

30 In view of my invention and disclosure variations and modifications to meet individual whim or particular need will doubtless become evident to others skilled in the art, to obtain all or part of the benefits of my invention without copying the structure shown, and I, therefore, claim all such in so far as they fall within the reasonable spirit and scope of my invention.

Having thus described my invention, what I claim as new and desire to secure by Letters Patent is:

1. In a rotary disintegrator, a casing, a rotary shaft therein adapted to turn at high speed, a 5 rotary disintegrator disc carried by said shaft, teeth located at the perimeter of the disc, open at the end and having their face surfaces sloping outwardly and rearwardly as respects the direction of rotation and having a circumferential 10 groove in an end face of the disc in the portion occupied by the teeth, a continuous fixed annular baffle above about the teeth, extending into the annular groove and a continuous fixed roughened annular surface within the casing 15 about the disc and adapted to receive the discharge from the disc.
2. In a high speed rotary disintegrator, a rotor shaft, means for rotating the shaft at high speed, a disc carried by the shaft having a plain disc surface upon the inner end surface of the disc and terminating in teeth, a source of supply of material to be disintegrated located above the center of the disc, means for controlling the supply, the upper faces of the teeth being circumferentially hollowed and upwardly projecting on the side toward the supply of material at the outer circumference of the teeth and a baffle, adapted to guide the discharge from the teeth, having an outwardly abrupt rib fitting down into the hollowed portion, a groove cooperating with the projection and an outwardly and downwardly sloping face across the outer edge of the disc and close to the outer disc edge. 20
3. In a rotor disintegrator, a casing, a rotatable shaft therein, means for rotating the shaft at high speed, a disintegrator disc carried by the shaft adapted to engage the product handled upon one end surface thereof and having the same end surface channeled near the circumference and flanged beyond the channeling closely adjacent the perimeter and there provided with impact teeth, the impact surfaces sloping outwardly and rearwardly as compared with the direction of rotation and an annular fixed baffle adjacent the disc surface, having an annular rib undercut on its radially outside edge within the channel and the baffle being grooved above the disc flange, and a continuous annular guiding surface in position to receive the material directed by the baffle and sloping downwardly and outwardly beyond the disc. 25
4. In a high speed rotary disintegrator, an inlet for material fed, a rotatable disc having peripheral teeth and an end face of the disc dished on the side toward the feed close to the outer part of the teeth, leaving the tooth ends relatively projecting axially at the outside of the disc, a casing about the disc, means for rotating the disc at high speed and a baffle extending as a rib into the dished portion continuously about the circumference of the disc and having a transversely and outwardly sloping portion close to the disc perimeter guiding the discharge, the radially outer edge of the rib adjacent the disc being abrupt and continuous in radial line with the axial teeth projections, whereby material fed breaks away from the baffle at this edge of the rib and is thrown into the axially extending projections of the teeth, as distinguished from following the contour of the baffle. 30
5. In a rotary impact disintegrator, a casing, a shaft therein, means for rotating the shaft at high speed, a disc on the shaft having a distributing end surface of diameter less than the 35
6. In a rotary impact disintegrator, a casing, a shaft, therein, means for rotating the shaft at high speed, a disc on the shaft having teeth at the perimeter grooved in their axial faces and open for discharge directly radially outward, a circumferentially continuous baffle extending into the groove and out of it and transversely across the outer faces of the teeth to receive the impact of the discharge from the teeth, and a second disc having its face against the back of the first disc, of larger diameter and having teeth about its perimeter free to discharge radially outward and grooved in their faces, whereby the discharge from the first teeth is driven axially across the teeth of the second disc. 40
7. In a rotary impact disintegrator, a casing, a shaft therein, means for rotating the shaft at high speed, two discs on the shaft of different diameters, the larger having its face adjacent the back of the smaller and the smaller having a distributing end surface of diameter less than the diameter of the disc, both discs having teeth at their perimeters open for discharge directly radially outward and circumferential end grooves through the teeth near the outer ends of the teeth leaving end tooth projections, the grooves and teeth of the larger disc extending beyond the teeth of the smaller disc, a circumferentially continuous baffle for each disc extending into the groove of the corresponding disc and abrupt at its outer edge within the groove to discharge radially through the ends of the teeth and a baffle flange for each baffle, close to the teeth of the corresponding disc, extending across the teeth ends and radially outward to receive the impact of the radial discharge and to guide the discharge transversely across the planes of the teeth, whereby both discharges are cleared to prevent cushioning and the discharge from the first baffle enters the groove of the second disc. 45
8. In a rotary disintegrator, a rotatable shaft, a motor adapted to rotate the shaft at high speed, a casing about the shaft, a disintegrator disc carried by the shaft having slots at its perimeter, sloping in slot length outwardly and away from the direction of slot rotation, the slots providing an annular series of teeth adjacent the outer edge of the disintegrator and a circumferentially continuous annular fixed baffle axially adjacent the teeth, said baffle having a substantially smooth surface facing said series of teeth, said surface being so arranged as to receive directly material discharged centrifugally from said disc. 50
9. A rotary disintegrator comprising a rotary shaft, means for rotating the shaft at high speed, a casing about the shaft, a plurality of disintegrating disc close together movable one with the other in the same direction, face to back of different diameter, each carried by the shaft and a baffle having fixed guiding surfaces circumferentially continuous for guiding the discharge 55
- 70
- 75

from one disintegrating disc into impact-receiving axial engagement with the outer rim of another, the baffle being continuous and internally substantially smooth.

10. In a high speed rotary disintegrator, a disc having teeth at the circumference spaced by slots and whose leading tooth surfaces constitute impact faces, a casing about the disc, supply means above the disc for feeding material to the center of the disc, whereby the friction from disc rotation causes revolution of the material and consequent centrifugal feeding of the material to the teeth, a continuous baffle above and about the disc terminating in an outwardly and downwardly sloping surface and a second disc of like character as the first mentioned disc and of larger diameter than it, having the teeth at the periphery in the second disc in line with the guided flow from the sloping surface.

11. In a rotary disintegrator, a rotatable shaft, a rotating disc carried by the shaft, a casing about the disc, means for rotating the shaft at high speed and an annular series of teeth carried by the disc separated by spaces providing inlet for the material to be disintegrated, the cylindrical end faces of the teeth being circumferentially channeled closely adjacent the circumference, providing an annular series of extending flanges, an annular continuous baffle above and about the disc extending into the channel of the disc, and a second annular continuous baffle above and around said series of flanges and having a downwardly and outwardly sloping surface and a second disc having an annular series of teeth and

35 spaces to which the material is led by the sloping surface.

12. In a rotary disintegrator, a casing, a rotatable shaft therein, a rotary disintegrator disc carried by the shaft, the outer edge of the disc being extended axially further on the side which is to receive the material to be handled than is true of the immediately adjacent end surface of the disc, a fixed continuous annular baffle extending toward the surface of the disc immediately adjacent the outer edge on the same side and beyond the outer edge of the disc on the same side and radially inwardly of the axial extension of the disc and lower than the uppermost portion 15 of said extension, the outer face of said fixed baffle extending inwardly and upwardly from the lower peripheral outer edge of said baffle, to provide a sharp peripheral edge for the discharge of material flowing along the bottom surface of said fixed baffle, and a fixed guide beyond the disc in the line of discharge therefrom.

13. In a rotary disintegrator, a plurality of concentric peripherally notched disintegrator discs in different planes, providing annuli of teeth open 20 at their sides and radial ends, said disc being of successively larger diameters from the point at which the material is received which is to be handled, means for supplying material to the smallest disc and a guide extending across the 25 radial ends of the teeth of the disc of smaller diameter receiving the material discharged from the outer edge of each smaller disc and directing it across and into the open sides of the teeth of the disc of the next larger size.

CHARLES T. ASBURY.
